THREAD CUTTER AND NIPPER FOR SEWING MACHINES

John P. Enos, Union, N. J., assignor to The Singer Manufacturing Company, Elizabeth, N. J., a corporation of New Jersey

Application March 21, 1947, Serial No. 736,157

18 Claims. (Cl. 112—252)

1

This invention relates to thread-severing devices for sewing machines and is particularly adapted for embodiment in household or family types of sewing machines for the purpose of severing the stitching threads connected to sewed articles.

A primary object of the present invention is to provide conveniently operable means, preferably in the form of an attachment, for severing the stitching threads, extending from a sewed article, at a predetermined distance from the stitching point, thereby to insure that the requisite lengths of threads are available in the sewing machine to commence a succeeding stitching operation. When the lengths of the severed threads extending from the stitching point are too short, the end of the needle thread will either be withdrawn through the eye of the needle, by the take-up, thereby unthreading the needle or it will be drawn down below the work in the succeeding stitching operation, thereby resulting in skipping of stitches and possibly also in clogging of the loop-taker of the sewing machine. On the other hand, an excessive length of thread extending from the stitching point results in thread wastage and occasionally in snarling of the thread.

A further object of this invention is to provide means, which is rendered effective upon severing of the stitching threads, for temporarily holding the severed ends of the threads extending from the stitching point. More specifically, the present invention aims to provide means for holding the severed ends of the threads until one or more stitches have been made in a succeeding sewing operation, which thread-holding means automatically releases the thread during the succeeding sewing operation and also when the usual sewing machine presser-foot is raised for insertion and removal of work.

With the above and other objects in view, as will hereinafter appear, the invention comprises the devices, combinations, and arrangements of parts hereinafter set forth and illustrated in the accompanying drawings of preferred and modified embodiments of the invention, from which the several features of the invention and the advantages attained thereby will be readily understood by those skilled in the art.

In the drawings:

Fig. 1 is an end elevation, on an enlarged scale, of a portion of a sewing machine fitted with one embodiment of the thread-severing and nipping device, a portion of the device being shown in section.

2

Fig. 2 is a front elevation, partly in section, of the same, also on an enlarged scale.

Figs. 3 and 4 are rear views, partly in section and on an enlarged scale, of the device shown in Fig. 1, of which Fig. 3 shows the thread-severing and -nipping element in raised position while Fig. 4 shows it in depressed position.

Fig. 5 is a top plan view, on an enlarged scale and partly in section, of the improved device.

10 Fig. 6 is a top plan view of a portion of the cloth-plate of the machine and of the arm which carries the lower thread-severing and -nipping block.

15 Fig. 7 is a detail sectional view of the complementary thread-severing and -nipping elements, showing the movable blade in a position it occupies prior to its final downward movement and lateral deflection into thread-severing relation with the stationary blade.

20 Fig. 8 is a detail sectional view of the complementary thread-severing and -nipping elements in the thread-severing relation thereof.

Fig. 9 is a view similar to Fig. 7, but showing the complementary elements in their relative position immediately after the thread has been severed and while it is nipped.

25 Fig. 10 is an end elevation, on an enlarged scale and partly in section, of a portion of a sewing machine fitted with a modified form of the invention.

30 Fig. 11 is a front elevation of the modification, also on an enlarged scale.

Fig. 12 is a rear elevation, partly in section, also on an enlarged scale, of the modification, with the thread-severing and -nipping element shown in full lines, in raised position and, in dotted lines, in depressed position.

35 Fig. 13 is a plan view of the construction shown in Fig. 11, with the presser-bar in section.

The invention is shown as applied to a conventional type of family sewing machine of which 1 designates a portion of the bracket-arm head in which is mounted, for endwise vertical movements, a needle-bar 2 which carries, in its lower end, an eye-pointed needle 3. Cooperating with the needle 3, in the formation of stitches, is a conventional loop-taker, not shown. Also mounted in the bracket-arm head, for endwise vertical movement, is a presser-bar 4 fitted with a presser-foot 5 which is retained thereon by the usual clamp screw 6.

The machine work-support 7, of which a portion is shown in Figs. 5 and 6, is recessed to receive a throat-plate 8, secured by fastening screws 9. The throat-plate is provided with the usual

needle-aperture 10 and slots 11 in which latter operates a feed-dog 12, in the usual manner.

Secured to the lower end of the presser-bar, 4, by the presser-foot clamp screw 6, is the improved thread-severing and thread-nipping device comprising a supporting shank 13 having an upper and forwardly extending steadyng arm 14 embracing the presser-bar 4 and the lower forwardly extending arm 15 apertured to receive the presser-foot clamp-screw 6 for securing the supporting shank on the presser-bar and against the shank of the presser-foot 5.

Integral with the supporting shank 13 is a laterally extending and vertically disposed supporting plate 16, on the front face of which is pivotally mounted, by a shoulder screw 17, a hand-lever 18. This lever is spring-urged upwardly into retracted position by a spring 19 having a coiled portion embracing the pivot screw 17. One arm 20 of the spring bears against the forwardly extending portion 14 of the supporting shank 13, while the other arm 21 thereof bears upwardly against the under side of a forwardly extending thumb-piece 22 of the hand-lever 18.

Pivotedly mounted at the rear side of the supporting plate 16, upon a shoulder screw 23, is an actuating lever 24, the free end of which is forked and has its upper tine 25 contacting the outer surface of the closed upper end of an inverted U-shaped thread-severing and -nipping member 26, of thin spring steel. The member 26 comprises a laterally yieldable thread-severing blade 27, having a sharpened cutting edge 27', and a laterally yieldable thread-nipping blade 28 having an unsharpened or rounded thread-engaging end 28'. The lower tine 25', of the actuating lever 24, is disposed between the blades 27 and 28 of the member 26 and in contact with the inner surface of the closed upper end thereof. Thus the lever normally urges the member 26 upwardly under the influence of the spring 19.

Motion is transmitted from the hand-lever 18 to the thread-cutter actuating lever 24, but in the opposite direction, through the medium of a shoulder screw 29 threaded into the lever 24 and having its shank passing through and engaging the walls of an inclined slot 30 in the hand-lever. The screw 29 passes through a clearance slot 31 formed in the plate 16.

Secured upon the actuating lever 24, near the pivot screw 23, is a spring 32, the free end of which bears against the outer face of the thread-severing blade 27 and urges it into contact with the side of the tine 25', thereby preventing vibration of the blade and insuring that it will be properly positioned relative to the cooperating ledger blade, later to be described.

Secured to and extending from the lower rear face of the plate 16 is a portion 33 forming, with the plate 16, a rectangular guideway for the inverted U-shaped member 26 which provides the thread-severing blade 27, and the thread-nipping blade 28. The guideway is wider than the spacing of the blades, thereby permitting the blades to move laterally and to center themselves with respect to a complementary stationary thread-cutting and -nipping member. Threaded into the outer wall of the guide-portion 33 is a thumb-screw 34 the free inner end of which contacts the thread-severing blade 27 during its downward movement, thereby preventing outward deflection of the upper portion of the blade. This causes the blade to be put under tension against the complementary stationary blade, thereby insuring a positive shearing of the

thread as later will be described. A coil spring 35 embraces the screw 34 and bears upon the head thereof and upon the portion 33, thereby frictionally retaining the screw in adjusted positions.

Disposed beneath the thread-severing and -nipping blades is a lower complementary stationary thread-severing and -nipping element comprising a ledger-block 36, pivoted, by a rivet *p*, for slight turning movement, upon the free end portion 37 of a curved supporting arm 38 which, in turn, is adjustably secured upon the work-support 7 by the fastening screws 39. The front edge 40 and the rear edge 41 of the ledger-block 36 are spaced more widely apart than the normal spacing of the blades 27 and 28, as shown most clearly in Fig. 7, so as to insure a thread-shearing and -nipping action upon the sewing thread *t* lying upon the block, when the blades 27 and 28 are depressed by the actuating lever 24. At its opposite ends, the block 36 is formed with portions 36^a, the upper surfaces of which are rounded and disposed within the normal plane of movement of the blades 27 and 28 and function to engage and spread the blades when they are depressed to sever and nip the thread. The slight pivotal movement of the block 36, under the thrust of the blades 27 and 28, causes it to be aligned with the blades in their downward movement.

The upper surface of the block 36 is milled off between the rounded end portions 36^a, thereby affording a horizontally disposed channel 36^b which receives the threads extending rearwardly from the stitching point and holds them in the paths of movement of the blades 27 and 28. The rear edge 41 of the block 36 serves as a stationary cutting edge which cooperates with the sharpened edge 27' of the movable cutting blade 27 in severing the thread.

A sheet metal housing 42, secured, by a screw 43, to an arm 16^a projecting rearwardly from the plate 16, affords protection for the moving parts and prevents accidental contact therewith by the fingers of the operator.

It will be observed that the thread-cutting and -nipping device is located in the line of seam formation in rear of but closely adjacent the needle. The position of the device is such that the thread extending rearwardly from the needle, after a thread-cutting operation, is sufficient to insure the beginning of the first stitch of a succeeding stitching operation, without wastage of thread.

Forwardly of the block 36, the arm 38 is provided with a raised member or portion 38^a having an inclined forward wall 38^b. This, together with the fact that the ends of the member 38^a and the rounded portions 36^a of the block 36 are inclined upwardly, facilitates passage of the work to and over the block 36.

In practice, the thread-severing and -nipping blades are normally maintained in elevated position to afford a clear and unobstructed passage of the work beneath the same. At the completion of the sewing operation, the work is advanced slightly beyond the block 36 thereby causing the sewing threads to rest upon the block within the channel 36^b. The operator then depresses the hand-lever 18 thus causing the thread-cutting and -nipping blades first to be lowered into contact with the rounded portions 36^a of the block 36, as shown in Fig. 7. It will be noted that, in this position, the blades 27 and 28 are in their normal or undeflected condition and are located inwardly

of their complementary cutting and nipping edges 41 and 40, respectively, of the block 36. Further depression of the hand-lever 18 causes the lower ends of the blades 27 and 28 to pass down over the rounded end portions 36^a of the block 36, thus deflecting the blades outwardly away from each other and bringing the cutting edge 27' into shearing relation with the edge 41 of the block 36, thereby severing the thread *t* as illustrated in Fig. 8. Still further depression of the hand-lever 18 causes the blades 27 and 28 to descend to the position illustrated in Fig. 9, in which position the blade 28 nips the end portion *t'* of the thread *t* between itself and the edge 40 of the block 36, thereby holding the thread end against movement toward the switch-forming mechanism during the formation of the first stitch of the succeeding sewing operation.

The lateral pressure of the blades 27 and 28 on the sides of the block 36 will cause the blades to remain in the position shown in Fig. 9 after the thread has been severed and nipped. Upward movement of the presser-bar and presser-foot, either under the action of the usual presser-lifter, not shown, for removal or insertion of work, or the lifting thereof by the action of the feed-dog during the next succeeding work-feeding movement, will cause the member 26, with its blades 27 and 28, to be elevated and freed from the block 36, whereupon the parts are returned to their retracted positions, as shown in Figs. 2 and 3, by the spring 19.

A modified form of my invention is disclosed in Figs. 10, 11, 12 and 13. In these figures, the parts which are the same as those shown in Figs. 1 to 9, and above described, are designated by the same reference characters. Further description of these parts is deemed unnecessary.

The modified construction comprises a supporting shank 44 secured to the presser-bar 4 by the usual presser-foot clamp screw 6. The shank 44 has a laterally off-set portion 45 (Fig. 13) to which is secured, by screws 46, a U-shaped guide member 47 within which is slidably mounted, for vertical reciprocation, an inverted U-shaped thread-severing and -nipping member 26 having a thread-severing blade 27 and a thread-nipping blade 28, as hereinbefore described in reference to Figs. 1 to 9, inclusive. Secured to the side walls of the member 47, by screws 48, and closing the open side thereof, is a second member 49, U-shaped in cross-section. This member 49 affords a slideway for a vertically disposed slide member 50 having, at its lower end, a laterally projecting finger-piece 51, the shank 52 of which projects through a slot 53 in the lower portion of the back wall of the member 49.

Secured to the slide member 50 and projecting therefrom and located between the blades 27 and 28 of the member 26 are lower and upper pins 54 and 55, respectively. A coil spring 56, located between the blades 27 and 28 of the member 26 and having its upper end projecting through an aperture 27^a in the closed end thereof, has its lower end surrounding the pin 54 and its upper end surrounding a pin 57, carried by the upper portion of the member 47. Thus the spring 56 normally maintains the slide member 50 in its uppermost position. Upward movement of the member 50 is limited by contact of the shank portion 52, of the finger piece 51, with the upper wall 58 of the slot 53 in the member 49. (See Fig. 11.)

As shown most clearly in Fig. 12, the pin 55 is located within and engages the closed upper end of the member 26. Therefore, upward movement

of the slide member 50, and the pin 55 carried thereby, lifts the thread-severing and -nipping member to its retracted or inoperative position shown in Fig. 10 and in full lines in Fig. 12.

The slide member 50 also carries a screw 59, the head of which overlies and is adapted to engage the outer surface of the closed upper end of the member 26. Thus as the slide member 50 is depressed, in opposition to the spring 56, by pressure applied to the finger-piece 51, the screw 59 forces the member 26 downwardly to perform the thread-severing and -nipping operations as above described in connection with the construction disclosed in Figs. 1 to 9, inclusive. Downward movement of the slide member 50 is limited by contact of an inturned finger 60, provided by the member 50, with a shoulder 61 provided on the rear wall of the housing member 47 (Fig. 11).

The modification disclosed in Figs. 10 to 13 inclusive functions, in its thread-severing and -nipping operations, the same as does the construction disclosed in Figs. 1 to 9, inclusive, which has already been described herein. Detailed description of the operation of the modified construction is therefore deemed unnecessary.

Having thus set forth the nature of the invention, what I claim herein is:

1. A thread-severing device for sewing machines, comprising, an endwise movable and laterally yieldable thread-severing blade; and a complementary ledger-block having a cutting edge and spaced rounded blade-deflecting surfaces merging with opposite ends of the cutting edge of said ledger-block, said blade-deflecting surfaces being positioned for initial engagement by said blade in the approach of said blade to said ledger-block.

2. A thread-severing device for sewing machines, comprising, reciprocable and relatively laterally-yieldable thread-severing and thread-nipping blades; ledger-means providing laterally spaced thread-severing and thread-nipping edges complementary to said blades but out of the normal path of movement thereof; means for moving said blades into contact with said ledger means; and guide means for laterally deflecting said blades into coacting relation with the respective thread-severing and thread-nipping edges.

3. A thread-severing device for sewing machines, comprising, laterally spaced and relatively laterally yieldable thread-severing and thread-nipping blades; a complementary ledger-block having a pair of edges spaced laterally from each other more widely than the normal spacing of said blades; means for moving said blades into contact with said ledger-block; and guide means for laterally spreading said blades into coacting relation with said edges.

4. A thread-severing device for sewing machines, comprising, laterally spaced and relatively laterally yieldable thread-severing and thread-nipping blades; a pivotally mounted ledger-block having a pair of thread-severing and thread-nipping edges spaced laterally from each other more widely than the normal spacing of said blades; means for moving said blades into contact with said ledger-block; and means carried by said ledger-block and cooperating with said blades for turning the block to align its edges with the blades and for laterally deflecting the blades into coacting relation with said edges.

5. In a sewing machine having stitch-forming mechanism, work-feeding mechanism, and a presser-device including a presser-bar and a presser-foot carried thereby; a thread-severing

and thread-nipping device comprising spaced apart and relatively laterally yieldable thread-severing and thread-nipping blades supported by said presser-bar and located in, and arranged transversely of, the line of seam formation; a ledger-block having thread-severing and thread-nipping edges cooperating, respectively, with said thread-severing and thread-nipping blades; and means supported by the presser-bar for moving said blades into thread-severing and thread-nipping relation with said edges.

6. A thread-severing device for sewing machines, comprising, a U-shaped member providing laterally spaced and resiliently yielding blades; a complementary ledger-block provided with a pair of edges spaced laterally from each other more widely than the normal spacing of said blades, said ledger-block being provided with upstanding portions having surfaces engaging said blades and spreading them into coacting relation with said edges; and means for moving said blades into engagement with said ledger-block.

7. A thread-severing device for sewing machines, comprising, a movable U-shaped member providing laterally spaced and resiliently yielding blades, one of said blades being sharpened to provide a cutting edge and the other of said blades having an unsharpened edge; and a complementary ledger-block having a thread-severing edge and a thread-nipping edge spaced from each other more widely than the normal spacing of the edges of said blades, said ledger-block being provided with spaced convex guide surfaces merging with said edges of the ledger-block and disposed in the path of movement of the edges of said blades.

8. A thread-severing device for sewing machines, comprising, a supporting member provided with a guideway; a U-shaped member providing laterally spaced and resiliently yielding blades movable in said guideway; a ledger-block provided with a pair of edges spaced laterally from each other more widely than the normal spacing of said blades, said ledger-block being provided with means for spreading said blades into coacting relation with said edges; adjustable means carried by said supporting plate for limiting the spreading movement of said blades; and means for moving said blades into engagement with said ledger-block.

9. A thread-severing device for sewing machines, comprising, a supporting member provided with a guideway; relatively laterally yieldable thread-severing and thread-nipping blades mounted for movement in said guideway; a hand-lever and an actuating lever oppositely directed and pivotally mounted upon said supporting member; a ledger-block; an operative connection with said hand lever for swinging said actuating lever; and an operative connection with said actuating lever for moving said blades into thread-severing and thread-nipping engagement with said ledger-block.

10. A thread-severing device for sewing machines, comprising, a supporting plate provided with a guideway; relatively laterally yieldable thread-severing and thread-nipping blades mounted for movement in said guideway; a hand-lever and an actuating lever oppositely directed and pivotally mounted upon opposite sides of said supporting plate; a ledger-block; an operative connection between said levers; and an operative connection between said actuating lever and said blades for moving the latter into thread-severing and thread-nipping engagement with said ledger-block.

11. In a sewing machine, in combination, stitch-forming mechanism including a reciprocating needle; a feeding mechanism including a feed-dog; a presser device including a presser-bar and a presser foot carried thereby; relatively laterally yieldable thread-severing and nipping blades supported for movement with said presser-bar; ledger-means providing thread-severing and thread-nipping edges complementary to said blades; means for moving said blades into engagement with said ledger-means; and means including said feed-dog and presser-foot for releasing said blades from said ledger means.

12. In a sewing machine, in combination, 15 stitch-forming mechanism including a reciprocating needle; spaced thread-severing and thread-nipping blades disposed in the rear of said needle and extending across the line of seam formation; a complementary ledger-block extending across 20 the line of seam formation and provided with a pair of edges adapted to cooperate, respectively, with said blades, and means for moving said blades into thread-severing and thread-nipping engagement with the respective edges of said ledger-block.

13. A thread-severing device for a sewing machine having a work-support, comprising, a reciprocal U-shaped member providing thread-severing and thread-nipping blades; a supporting member secured to said work-support; a ledger-block carried by said supporting member and provided with a pair of edges adapted to cooperate, respectively, with said thread-severing and thread-nipping blades; a work-deflecting 35 member carried by the supporting member in advance of said ledger-block for upwardly deflecting the work over said ledger-block; and means for moving said blades into coacting relation with the edges of said ledger-block.

14. A thread-severing device for sewing machines, comprising, an inverted U-shaped member providing laterally resilient blades, one of said blades having a sharpened end; a ledger-block provided with laterally spaced edges complementary to said blades; means for advancing said blades toward and slidingly past said edges, to sever and nip sewing threads extending over said ledger-block; and yielding means for retracting said blades.

15. In a sewing machine, in combination, stitch-forming mechanism including a reciprocating needle; work-feeding mechanism; a ledger-block disposed rearwardly of the path of needle reciprocation and providing substantially parallel thread-cutting and thread-nipping edges extending across the line of seam formation; an inverted U-shaped member providing laterally resilient blades having the ends thereof substantially parallel to said edges of the ledger-block and normally spaced apart less than the width of said ledger-block; means for endwise moving said blades toward and slidingly past said edges into ledger-block clamping position; and means brought into effective action by operation of said work-feeding mechanism for retracting said blades from said ledger-block.

16. A thread-severing and -nipping device for sewing machines, comprising, a U-shaped guide member; a second U-shaped member comprising laterally resiliently yielding blades movable within said first guide member; a complementary ledger-block provided with a pair of edges spaced laterally from each other more widely than the 75 normal spacing of said blades; means for de-

pressing said second U-shaped member into co-operative relation with said ledger-block; and means for returning said second U-shaped member to an inoperative position spaced from said ledger-block.

17. A thread-severing and -nipping device for sewing machines, comprising, a U-shaped guide member; a second U-shaped member affording laterally resiliently yielding blades movable within said first guide member; a complemental ledger-block provided with a pair of edges spaced laterally from each other more widely than the normal spacing of said blades; means for moving said second U-shaped member into contact with said ledger-block and for spreading said blades into operative relation with the edges thereof; and means carried by said first U-shaped guide member for adjustably limiting the spreading movement of said second U-shaped member.

18. A thread-severing device for sewing machines, comprising, a fixed U-shaped guide-member; an endwise movable U-shaped member comprising laterally resiliently yielding blades

disposed within said first U-shaped member; a complemental ledger-block; a cover member embracing the open end of said first U-shaped member; an endwise movable slide-member disposed within said cover member and having a projecting finger-piece for manually depressing said slide-member; an operative connection between said slide-member and said endwise movable U-shaped member for actuating the latter into thread-severing relation with said ledger-block; and a spring connection between said U-shaped members for restoring said endwise movable U-shaped member to an inoperative position relative to said ledger-block.

15 JOHN P. ENOS.
